CLAIM

The ornamental design for a combined car jump starter and tire inflator, as shown and described.

DESCRIPTION

FIG. 1 is a front and top perspective view of a combined car jump starter and tire inflator, showing my new design.

FIG. 2 is a rear and top perspective view of a combined car jump starter and tire inflator.

FIG. 3 is a front view of a combined car jump starter and tire inflator.

FIG. 4 is a rear view of a combined car jump starter and tire inflator.

FIG. 5 is a left side view of a combined car jump starter and tire inflator.

FIG. 6 is a right side view of a combined car jump starter and tire inflator.

FIG. 7 is a top view of a combined car jump starter and tire inflator; and,

FIG. 8 is a bottom view of a combined car jump starter and tire inflator.

The broken lines in the drawings depict portions of the combined car jump starter and tire inflator that form no part of the claimed design.

1 Claim, 8 Drawing Sheets
